PORATION OF NEW YORK

WIRE-TYING MACHINE

Application filed October 27, 1933. Serial No. 671,241.

This invention relates to improvements in wire tying machines. In its entirety it seeks to provide a compact and convenient organization of elements whereby a wire disposed about a package or box may be tightly tensioned, its overlapping bights thereafter tied securely together, one end of the wire cut free from the tensioning means and the tied wires automatically disengaged from the machine.

10 The invention also seeks to provide a disposition and relative arrangement of the various parts whereby they may perform their functions wholly above the lower surface of the base in order that the machine may operate as near to or remote from an edge of the package as may be desired. It also seeks to so locate and arrange the levers or actuators of the tensioning and tying devices that the machine may be operated by hand with the greatest convenience, ease and speed.

The invention consists of the various elements and their combinations hereinafter described and set forth in the claims.

In the drawings forming part of this specification, and in which like reference numerals designate corresponding parts, the various features of the invention are shown in their most approved form and arrangement. In said drawings,—

20 Fig. 1 is a front elevation, parts being broken away, showing the machine with the wire adjusted in position ready to begin the tensioning operation.

Fig. 2 is a similar view showing the parts as disposed at the end of the tensioning operation and ready to begin the tying operation.

Fig. 3 is a similar view showing the parts as disposed near the end of the twisting operation and the beginning of the cutting operation.

Fig. 4 is a similar view showing the parts as disposed immediately after the ejecting operation.

Fig. 5 is a rear elevation, parts being broken away, showing the operating connections of the ejector.

Fig. 6 is a plan view showing the parts as disposed after the tying operation has been

completed and before the ejecting operation has begun.

Fig. 7 is a sectional elevation taken on the line 7—7 of Fig. 6 looking in the direction of the arrows.

Fig. 8 is a detail showing a member of the ejector.

Fig. 9 is a sectional view of the cutter taken on the line 9—9 of Fig. 7 and looking in the direction of the arrows.

Figs. 10, 11 and 12 are detail views showing the ejector having a retaining device for the wire in modified forms.

Referring now to the specific features as shown in the drawings, 1 is the base of the machine, preferably consisting of a substantially cast iron plate, on which all the moving parts of the machine are mounted. This base is usually rectangular in shape as will be noted by reference to Fig. 6. Integral with the base are the front and rear bearing blocks 2 and 3 in which is mounted the main shaft 4. The block 2 is cast in one piece and has a central bore 5 to receive the shaft 4. The rear bearing block 3 is made in two parts 75 having a cap 6 which is held in place by screw bolts 7 and 8. Fixed on the front end of the shaft 4 and outward from bearing block 2 is a spiral twisting gear 9 which meshes with the slotted twisting pinion 10. Pinion 10 is provided with journals 12 and 13 mounted in bearings provided on the front edge of the base 1. The bearings for these journals are formed on projections extending from the front edge of the base, the upper half of the bearings being cut in the projections 14 and 15 integral with the base and the lower half of the bearings being cut in the block 16 rigidly secured to the bottom of the base by screws 17. The slot 18 in the twisting pinion 10 extends slightly beyond the center of the pinion and its width is slightly in excess of the diameter of the wire upon which the machine is designed to operate, so that two bights of the wire may lie side by side in the slot but cannot move one over the other. The journals 12 and 13 are also provided with slots 19 and 20 aligned with, but considerably larger than, the slot 18 to allow room for the parallel bights of the wire to

be twisted together. Rigidly fixed on the shaft 4 is a driving ratchet wheel 21 operated by the oscillating ratchet lever 22 loosely centered on the shaft 4. For this purpose lever 22 is provided with a pawl 23 having a spring 24 to keep it pressed against the ratchet wheel 21. It is obvious that an oscillating to and fro movement of lever 22 will rotate shaft 4 and the twisting gears 9 and 10.

It is important that, at the end of each twisting operation, the twisting pinion 10 always come to rest in the same predetermined position with the slot 18 opening outward to receive the wire for the next operation. For this purpose a locking device is provided which is adapted to automatically lock the twisting gears in said predetermined position at the end of each twisting operation. This locking device may be variously arranged but, in the present instance, it consists of a vertically disposed bolt 25 which works through an orifice 26 in the top of the bearing block 2 into a recess 27 cut in the shaft 4. When this bolt has engaged the recess 27, the shaft 4 and twisting gears are locked against movement with slot 18 in the desired position. The bolt 25 is operated by lever 28 fulcrumed on a stud 29 fixed in the top of bearing block 2. Spring 30 serves to press the bolt 25 into the recess 27 whenever the latter registers with the bolt.

The machine is provided with suitable tensioning means which will now be described. 31 is a tension head having suitable slots cut in its periphery and rigidly fixed on the shaft 32 which turns in a bearing 33 integral with the base. Shaft 32 may be held in place by a nut 34 on its inner end. 35 is a ratchet wheel also rigidly fixed on the shaft 32. If desired, it may be made integral with the tension head 31. Loosely centered on shaft 32 is an oscillating ratchet lever 36 provided with a pawl 37 having a spring 38. A dog 39, having a spring 40, is provided to engage the ratchet wheel 35 and prevent retrograde movement thereof. It is desired to have the locking device so arranged as to be released automatically at the end of the tensioning operation. For this purpose lever 36 is so located with respect to the locking device that lever 28 of the latter is in the path of movement of lever 36. Thus lever 36 at the end of its forward throw engages lever 28 and retracts bolt 25 from recess 27 and unlocks the twisting devices. It will be seen that both levers 22 and 36 have a to and fro movement in upright planes substantially parallel, and that both handles extend in the same general direction in reference to the base and are capable, especially in rest position, to extend over the edge of the base of the machine that is at right angles to the edge along which the bights of wire extend, thus the levers ex-

tend in lengthwise relation to the bights of wire as held in the machine.

For the purpose of holding the two parallel bights of the wire in fixed position for the twisting operation, there are provided two wire holding jaws or wire holders projecting outward from the forward edge of the base and having narrow slots therein to receive the wires. These holding jaws are located on either side of the twisting pinion 10 and suitably spaced therefrom. The holding jaws 41 and 42 located on the right of the pinion 10, looking from the rear of the machine, are provided by a tubular member 43 rigidly fixed in and projecting from the front edge of the base and provided with wire receiving slots 44 and 45. The tubular member 43 is utilized to provide not only the holding jaws 41 and 42 but also part of the cutter to be presently described. 46 and 47 are the other holding jaws projecting from the front edge of the base. They provide the wire holding slot 48 in alignment with the slots 44 and 45. These slots are in alignment with the slot of the twisting pinion 10 when the latter is at rest in normal position.

49 is a rotatable cutter consisting of a cylindrical member fitting in the tubular member 43 and projects at the rear beyond that part of the base in which this tubular member is fixed, see Fig. 9. It is provided on its rear end with a crank arm 50 provided with a pin 51 which serves to limit the backward movement of the arm by striking against the upper surface of the base. A spring 52 bears against the pin 51 to hold the arm in its normal backward position. The upper half of the cylindrical cutter is cut away at its front end to provide the cutting edge 53 and to permit the reception of the wires in the slots 44 and 45, as shown more clearly in Fig. 9. The cutting edge 53 of the cutter is cut away at its rear to provide a recess 54 so that only the forward wire will be severed when the cutter is actuated. The cutter is arranged to be operated at the end of the twisting operation. For this purpose, the ratchet wheel 21 carries a pin 55 which takes under the end of the cutter arm 50 at the end of the twisting operation, and by elevating this arm rotates the cutter. The pin 55 is so mounted on the wheel 21 that the cutter arm 50 falls from the pin just prior to the falling of the bolt 25 into recess 27, thus the cutting operation is completed at a very small time interval ahead of the locking of the twisting pinion against further movement.

After the machine has completed its work of tensioning, twisting and cutting a wire encircling a package, the tensioned wire is left in the slots of the wire holders and twisting pinion, thereby holding the machine firmly down upon the package. Prior to the present invention there has been no satisfactory

means in machines of this same general character for disengaging the tied and tensioned wire from the machine and this could only be accomplished by much exertion on the part of the operator with accompanying loss of time.

5 The present invention overcomes this difficulty by providing means for automatically disengaging the tied and tensioned wire from the machine by ejecting it from the holding 10 and twisting slots. This is done immediately after the cutter has been operated and without any appreciable effort on the part of the operator and with no loss of time. In carrying out this part of the invention there are 15 provided two thrust rods 56 and 57 which slide to and fro in apertures formed in the base on either side of the twisting pinion, 10. 58 is another thrust rod which slides on the outer side of the holding jaw 46 or within a 20 recess formed in this jaw as may be noted in Figs. 1 and 2. The rear ends of these thrust rods are secured to and carried by a cross-bar 25 59 provided with a pin 60 which enters a cam member 62. Cam member 62 has an inner 30 tubular portion 63 sleeved on the shaft 4 at the rear of lever 22. It is held in normal position by any suitable means such as a coiled spring 64, one end of which is secured in the cam member 62 and the other end of which is 35 secured in the cap 6 of the bearing block 3. A nut 65, threaded on the shaft 4, holds the tubular member 62 in position against lever 22. Cam member 62 is rotated on the shaft 4 by means of lever 22. For this purpose the 40 lever is provided with a pawl 66, having a spring 67, and the toe of the pawl is arranged to engage a lug 68 on the periphery of cam member 62 whenever lever 22 is sufficiently depressed, or pulled toward the operator as 45 he stands on the right side of the machine, as shown in Fig. 5. This downward movement of lever 22 and rotation of cam member 62 moves forward the thrust rods 56, 57 and 58 so that their forward end will bear force- 50 ibly against the wire and eject it from the holding and twisting slots, thereby disengaging the wire from the machine. When the thrust rods have reached the limit of their forward movement, a continued downward 55 pressure of the lever 22 brings the heel 69 of pawl 66 against a tripping stud 70 secured to the base, thereby disengaging the pawl from lug 68 and permitting cam member 62 to be rotated by its spring back to normal position.

55 This return movement of the cam member returns the thrust rods to their rearward or normal position in which they are stopped by the pin 60 striking one end of the slot 61. Thrust rod 58 slides on the lower part of the 60 base and against the recessed side of the holding jaw 46.

65 Referring to Figs. 1 and 2, it will be noted that the jaw 47 is recessed to such an extent that it receives therewithin practically the full width of the thrust rod 58. As so posi-

tioned in the recess this thrust rod lies directly above the active part of holding jaw 47, and cooperates to a slight extent with jaw 47 as will later be explained to hold the wire from slipping through the machine during 70 the tensioning operation. In such preferred construction jaw 46 functions only to guide thrust rod 58 and to act as a reinforcing support therefore. The actual constructions of these parts may be variously varied without changing their functions. For instance, the width of jaw 46 may be greatly decreased and the width of the thrust rod materially increased, and the catch or retaining device 80 positioned within the structure of the thrust rod thereby being protected against being jammed or broken off. Such variations in the structures of these parts have been made and have been found to be very satisfactory in 85 use.

The forward end of thrust rod 58 is provided with a recess 71 preferably a right angle recess as shown in Fig. 8. The bights of the wire as they are inserted in the machine are received within this recess 71 and substantially all of the upset head 74 on the end of the wire (see Figs. 1 and 2) is received against the side of the thrust rod 58; the side of the jaw 47 receiving only a small proportion of the head as may be noted by reference to Figs. 8, 10, 11 and 12. When the tensioning operation takes place the head 74 is drawn tight against the side of the thrust rod and if the tension is too great the head becomes jammed in the right angle recess 71 and possibly against the top of jaw 47. The movement of the thrust rod 58 in assisting to eject the wire from the machine is such that it merely passes over the top of jaw 47 until the wire is carried beyond the end of that jaw and the wire then, in released position, falls or snaps down on to the package by reason of its taut condition. It will be seen that with this type of construction, i. e., where the assisting ejector or thrust rod receives and holds the head of the wire, that there may be any amount of jamming of the wire head but no specially exerted force is required to move it out of its holder for the holder moves until the wire is free to fall to the container or package. Thus there is no movement of the jammed head relative to its main holding member until the wire drops from the machine.

120 From the foregoing it will be seen that the rod 58 and the jaw 47 act as a compound means for holding portions of the bights of wire as the rod 58 moves over the stationary jaw 47. It is preferred to have the recess 71 formed of uniform depth or height throughout its length so that it will receive any portions of the wire except the upset portion. Thus the wires may be inserted into the machine in any careless manner so long as the 130

upset portion which later bears against rod 58 is on one side of the rod.

When the tensioning operation takes place the upset portion is drawn into contact with the rod 58 which may be considered as the movable member or movable portion of the compound means. As will be noted the jaw 47 is a projection from the base 1 and may be considered as the "other portion" of the compound holding means. Normally the recess 71 is over the top of the stationary member or jaw 47 and due to the movement of rod 58 these parts are rearranged so that the wires are carried to release position. It will be noted in this connection that retaining catch 80 remains in its normal relative relation without movement to the wires until the wires have a movement relative to the thrust rod 58.

It is advantageous to provide the machine with a retaining device to retain the wire in place during the tying operation. Such a device is shown in several modified forms in Figs. 8, 10, 11 and 12.

In Fig. 8, the retaining device is in the form of a finger having its forward surface inclined, as shown, and formed as part of a latch 80 secured by means of a pivot 81 on the ejector member 58. The latch 80 is held down in normal position by any suitable means exemplified by a spring wire 82, the forward end of which enters a perforation in the latch 80, and the rear end of which bears upon the base 1. This spring wire 82 passes under the pivot 81. When the wires 76 and 77 are adjusted in position in the holding slot 48 between the wire-holding jaws 46 and 47, they are pushed against the front inclined surface of the retaining device which rises in response to this pressure and permits the wires to enter the formed slot. The retaining device then returns to normal position under pressure of its spring 82 to maintain the wires in place. When the ejector member moves forward, the retaining device 79 is carried forward beyond the end of the jaw 47. It thus automatically moves out of its normal retaining position by the movement of the ejector member 58, but it is not raised vertically in respect to the wire held by the thrust rod 58 and jaw 47.

In Fig. 10, ejector member 83 takes the place of ejector member 58. Ejector member 83 occupies the same position as does ejector member 58, but the former is pivotally mounted at its rear end on one end of the cross bar 59. Its front end has integrally formed thereon the retaining device 84 similar to retaining device 79. A spring 85 acts to yieldingly hold the ejector member down on the base with the retaining device 84 normally in retaining position. The retaining device 84 moves out of its retaining position with the forward movement of the

ejector member 83 in the same way as does the retaining device 79.

In Fig. 11, the retaining device 86 has the same location and structure as retaining devices 79 and 84. Retaining device 86, however, is formed integrally with the latch 87 pivotally mounted by means of pivot pin 88 on the base 1, or at the rear of holding jaw 46 which projects from the base. The latch 87 has an inclined rear surface 89 against which works a pin 90 carried by ejector member 58. A spring 91 bearing against the rear end of latch 87 holds the retaining device in its normal retaining position. In this case, when the ejector 58 moves forward, pin 90 strikes inclined surface 89 and lifts the retaining device upward out of its retaining position.

In Fig. 12, the retaining device 92, shaped and located like the other retaining devices just described, is formed integrally with the latch 93 pivotally mounted on pivot pin 94 carrier by ejector member 58. A spring 95 secured to ejector member 58 bears under a pin 96 on the latch 93 to hold the retaining device in its normal retaining position. 97 is a pin fixed on the base 1, or the rear end of holding jaw 46, and it takes against the inclined surface 98 on latch 93 when the ejector member 58 is moved forward and lifts the retaining device 92 upward and out of its retaining position. If desired a latch having a retaining device may be mounted on one or both of the ejector members 56 and 57. In the drawings such a latch 99 is shown mounted on the forward end of ejector member 56. It has the form of the forward end of latch 80 of Fig. 8 and its shank enters a slot in the end of member 56 and is therein pivoted on a horizontal pin. It hangs in retaining position by gravity and acts in the same manner as latch 80. It will be noted that in all of these various arrangements of the retaining device, it automatically moves out of its retaining position by a moving part of the machine which, in the instances shown, is the ejector.

It will be noted that the lever 22 and cam piece 62 constitute power means for operating the ejector. It will also be noted that, after the ejector has been operated and then returned to normal position upon the depression of lever 22 and tripping of pawl 66, the ejector is thereupon locked in normal position and lever 22 is locked in its lowermost position by locking bolt 25 which has already entered recess 27 to lock the twisting gears, and neither of these elements can be moved until bolt 25 is retracted. The locking of the ejector in normal position makes certain that it will be in its proper place for the next operation. The lever 22, when locked in its lowermost position, affords a convenient immovable handle for carrying the machine from place to place.

The operation of the machine is as follows. The machine is placed upon the package or box 72 to be wire-tied in the position shown in Fig. 1. The operator, standing on the right side of the machine, takes a wire 73 and inserts one end thereof into the formed slots and twisting slot of pinion 10. The wire is provided at one end with a head 74 to bear against the thrust rod 58 and jaw 47 which provide the slot 48. The wire is then passed around the package or box 72 and again through the holding and twisting slots and its free end 75 is engaged in the tension head 31. This positions the two overlapping bights 76 and 77 in the holding and twisting slots with the bight 76 at the back of the slots and directly above the recess 54 of the cutter, see Fig. 9. The operator grasps lever 36 with his right hand and lever 22 with his left hand and oscillates lever 36 to and from him so as to rotate the tension head and thereby tension the wire about the package; head 74 holding its end of the wire securely in the machine. Lever 36 should be oscillated near its extreme forward position so that at the end of the tensioning operation it may be depressed against lever 28 of the locking device, as shown in Fig. 2, to retract locking bolt 25 and unlock the twisting devices. The operator then oscillates lever 22 until the twisting gear 9 and its shaft 4 have made one complete revolution, whereupon locking bolt 25 snaps into its recess 27 and arrests the twisting operation and again locks the twisting devices in normal position. Gear 9 and pinion 10 are so proportioned that one rotation of gear 9 produces three rotations of pinion 10 so that twisting slot 18 of pinion 10 is back in its initial position the moment locking bolt 25 enters recess 27. Just before the completion of the twisting operation, pin 55 on ratchet wheel 21 engages cutter arm 50 to rotate cutter 49. This cutting action is so timed that it is completed substantially simultaneously with the return of pinion 10 to its initial position and the relocking of shaft 4 by bolt 25. At the same time pin 55 clears cutter arm 50 and the cutter is returned by its spring to normal position. Fig. 3 shows the parts in the position they occupy just before, and Fig. 4 shows them just after, the cutting operation has been completed. By reference to Fig. 9, it will be seen that, by reason of recess 54, the cutter does not act upon bight 76 but only upon bight 77 whereby that end of the wire secured to the tension head 31 is cut off. Lever 22 is oscillated most conveniently between its upright position and its horizontal position farthest from the operator.

The completion of the twisting and cutting operations is indicated to the operator by the sound of the bolt 25 snapping into the recess 27. At this time the wire is under tension and the twisted bights thereof, as

they lie in the twisting and holding slots, are binding the machine firmly down upon the package and it is necessary to free the machine from the wire. The operator accomplishes this result by pulling lever 22 towards him, whereupon pawl 63, by engaging pin 68 on cam sleeve 62, rotates this sleeve and forcibly drives thrust rods 56, 57 and 58 against the twisted wire bights so that they are instantaneously ejected from the twisting and holding slots and snap down upon the surface of the package by reason of the taut condition of the wire. As the thrust rods reach their outward limit of movement, heel 69 of pawl 60 strikes tripping stud 70 thereby disengaging pawl 66 from lug 68 and permitting spring 64 to return sleeve 62 and the ejector to normal position in which they are locked by the locking device. All the parts are now back to normal position and the machine is free to be lifted from the package for the next operation.

The wire to be employed in this machine may be of any suitable size or kind or shape so long as it may be threaded into the particular size of machine and permit the tensioning to be properly performed. It has been found by experience that the most efficient operation of any wire tying machine is obtained when the end of the wire which is anchored during tensioning is held in a manner that permits easy ejection after the twisting operation. Heretofore the usual method of anchoring one end of the wire is to have it positioned between two jaws which draw closer and closer together as the pull on the wire increases thereby pinching the wire to a greater and greater degree. Usually the engaging surfaces of the jaws are of cam shape and are provided with burrs which are forced into the wire as the tensioning increases. This type of anchoring means requires that there be a special attachment associated with the machine to open the jaws so as to withdraw the machine from the wire after the twisting operation has been completed.

The wire tying machine herein described is constructed in an improved manner which provides for an improved means for anchoring one end of the wire to allow proper tensioning, and after the completion of the twisting operation permits the wire to be quickly and easily ejected from the machine. This improved means for anchoring does not require a special attachment to the machine for freeing the anchored end of the wire, nor does it require a special or separate operation to move the wire out of the machine.

The wire preferably employed is provided with the upset portion or head 74 on one end or is otherwise deformed to prevent its being pulled through the machine during the tensioning operation. This upsetting may

be readily accomplished, or the wire may be purchased in the open market. This improved machine was developed and is used with wire of this nature, and by this means the efficiency of the machine is greatly increased as well as permitting a great saving in time during its operation. Any particular shape or type of upset head may be made but I prefer that the upsetting be at the end of the wire and to have the head in the shape as shown at 74 in Fig. 2. It will be seen that the end of the wire with the upset head may be quickly threaded between the thrust rod 58 and jaw 47 and that it is anchored in position by reason of the co-operation of the head with the rod and jaw without in any way becoming jammed or pinched so that it is not easily ejected after the twisting operation has been completed.

It will be seen that when the operator takes his position at the right side of the machine for the insertion of a wire in the holding and twisting slots, it is unnecessary for him to move from that position throughout the entire operation of the machine. Standing in this position he is facing the operating levers and oscillates first one and then the other to and from him in upright parallel planes and parallel with the wire enclosing the package. Thus he is able to apply his power with the least exertion and with the greatest convenience, at the same time holding the machine steady by means of the levers firmly grasped in his two hands.

It will be noted that lever 22 is located substantially in the middle of the machine and its steadyng effect is therefore greatly enhanced. After the tensioning operation has been completed lever 36 is employed for steadyng purposes while twisting handle 22 performs its operating functions. It will also be seen that by disposing lever 28 of the locking device in the path of movement of tensioning lever 36, the locking device is automatically disengaged by the tensioning lever upon the completion of the tensioning operation. And it will further be seen that after the operator has positioned the wire about the packages and grasped the levers in his two hands, that he is able to complete the entire operation without taking his hands from the levers. These various advantages enable the operator to work the machine with increased speed and with greater convenience and ease than has heretofore been attainable in machines of this general character.

The term "wire", as used in this specification, includes not only the ordinary round wire of commerce but also flat banding which, in this art, is also known as flat wire.

While the various features of the invention have been shown and described in what is considered to be their best form and arrangement, it is to be noted that these features may be variously modified in struc-

ture and arrangement without departing from the invention. This applies particularly to the ejector whose automatic arrangement is believed to be broadly new. It is also to be noted that many of the features of the invention are adaptable for use in a power driven as well as in a hand-operated machine.

What is claimed is:

1. In a wire tying machine the combination of a base, tying means and tensioning means mounted thereon, oscillating levers for operating said tying means and said tensioning means, both levers extending from the machine in the same general direction and in lengthwise relation to the wire held in the machine, and pawl and ratchet means interposed between the levers and the tying means and the tensioning means to transmit the movements of the levers to said tying means and to said tensioning means.

2. In a wire tying machine, the combination of a base, twisting gears and a tension head mounted thereon, and hand-operated ratchet levers for said twisting gears and tension head mounted so as to operate wholly above the base and move to and from the operator in parallel planes parallel to the wire upon which the machine is operating.

3. In a wire tying machine, the combination of a base, twisting gears and a tension head mounted thereon, and hand-operated ratchet levers for said twisting gears and tension head mounted so as to operate wholly above the base and to and from the operator in parallel planes parallel to the wire upon which the machine is operating, and in their forward thrust to actuate the twisting gears and tension head.

4. In a wire tying machine the combination of a base, means on one side of said base for receiving bights of wire to be tied, tensioning means and tying means mounted on said base, the axis of said tensioning means being at right angles to the bights of wire and substantially parallel to the top surface of the base, a gear included in said tying means for operating a twisting pinion also included in said tying means, a shaft for carrying said gear, said shaft being located at right angles to the wire and substantially parallel to the top surface of said base, levers for operating said tensioning means and said tying means, one of said levers operating in an upright plane substantially parallel to the wire upon which the machine is operating, and an ejecting means for forcibly moving said wire from said machine, said ejecting means operated by the lever that operates said tying means.

5. In a wire tying machine the combination of a base of substantially rectangular shape and arranged to receive along one edge thereof bights of wire to be tied, tensioning means and tying means mounted on said base and

arranged to operate upon said bights of wire, levers for operating said tensioning means and said tying means, said levers extending over an edge of said base that is at right angles to the edge which receives the wire, said levers adapted to be moved to and fro in upright planes, and an ejecting means for forcibly moving said bights of wire after tying from said machine, said ejecting means operated by the lever that operates the tying means.

6. In a wire tying machine the combination of a base of substantially rectangular shape, means mounted on one of the longer edges of said base for receiving bights of wire to be tied, tensioning means mounted on said base and arranged to receive one of the bights of the wire, tying means arranged to tie together the wire bights after tensioning, operating levers for said tensioning means and said tying means, said levers being so positioned with respect to the base that both are capable of extending over one of the shorter edges of said base, said levers being arranged to have a to and fro movement for operating said tensioning and said tying means, and pawl and ratchet means interposed between the levers and the tensioning means and the tying means to transmit the movements of the levers to said tensioning means and to said tying means.

7. In a wire tying machine the combination of a base, tensioning means and tying means mounted on said base, levers extending in the same general direction for operating said tensioning and said tying means, the lever for operating said tying means being a straight lever and the lever for operating said tensioning means being somewhat offset to the side along its length to give space between the free ends of said levers, and a locking means for said tying means, said locking means adapted to be moved by the lever associated with said tensioning means to free said tying means for operation.

8. In a wire tying machine the combination of a base, tensioning means, tying means, and ejecting means, said tying means comprising a pinion for twisting together two bights of wire, a gear for operating said twisting pinion, a shaft having said gear rigidly supported thereon, said shaft also supporting a ratchet wheel and an ejector cam member, and levers for operating said tensioning means and said tying means, the lever for said tying means being loosely mounted on said shaft and in operative relation to said ratchet wheel and to said ejector cam member.

9. In a wire tying machine the combination of a base, means on said base for tensioning two bights of wire received in said machine, means also mounted on said base for twisting said wires, and means for ejecting the twisted wire from the machine; levers for

operating said tensioning means, said twisting means and said ejecting means; said tying means including a pinion for twisting the wires and a gear for driving said pinion, a shaft having said gear rigidly supported on the extreme end thereof; said shaft also carrying a ratchet wheel, the lever which operates said tying means through said ratchet wheel, and an ejector member; and two bearing supports for said shaft, one of said supports engaging said shaft between said gear and said ratchet wheel and the other support engaging the shaft at its extreme end and next to said ejector member.

10. In a wire tying machine the combination of tensioning means, tying means, a locking device for locking the said tying means in predetermined position, said tying means having a wire twisting pinion, a gear for driving said pinion, a shaft for carrying said gear and for imparting movement thereto, a ratchet wheel rigidly mounted on said shaft, a lever movably mounted on said shaft and arranged to drive said ratchet wheel, a pawl carried by said lever and arranged to engage said ratchet wheel to move the same in response to movement of said lever, a bearing for said shaft, said bearing arranged to receive the portion of said shaft between said gear and said ratchet wheel, said locking device mounted on said bearing and arranged to engage part of said tying means to hold said tying means in a pre-determined locked position, and means associated with another part of said machine for loosening said locking device to allow said tying means to be operated.

11. In a wire tying machine, the combination of a base, twisting gears comprising a pinion and driving gear, said driving gear having a shaft extending substantially across said base and at an angle to the axis of the twisting pinion, a ratchet wheel fixed on said shaft, an oscillating ratchet lever loosely mounted on the shaft and acting in one direction of its throw only to rotate the shaft, and tensioning means including an operating lever mounted on the base at one side of the twisting gears, said levers operating in upright substantially parallel planes.

12. In a wire tying machine, the combination of a base, twisting gears comprising a pinion and driving gear, said driving gear having a shaft extending across the base from front to rear and at a right angle to the axis of the twisting pinion, a ratchet wheel fixed on said shaft, an oscillating ratchet lever loosely mounted on the shaft and acting in one direction of its throw only to rotate the shaft, and tensioning means including an operating lever mounted on the base at one side of the twisting gears, said levers operating in upright parallel planes.

13. In a wire tying machine, the combination of a base, twisting gears comprising a

pinion and driving gear, said driving gear having a shaft extending across the base from front to rear and at a right angle to the axis of the twisting pinion, a ratchet wheel fixed on said shaft, an oscillating ratchet lever loosely mounted on the shaft and acting in one direction of its throw only to rotate the shaft, and tensioning means including an oscillating ratchet lever mounted on the base at one side of the twisting gears, said levers operating in upright parallel planes.

14. In a wire tying machine, the combination of a base, twisting gears comprising a pinion and driving gear, said driving gear having a shaft extending across the base from front to rear and at a right angle to the axis of the twisting pinion, a lever centered on said shaft for actuating the same, and tensioning means including an operating lever mounted on the base at the right side of the twisting gears, said levers operating in upright parallel planes from the right side of the machine.

15. In a wire tying machine, the combination of a base, twisting gears comprising a pinion and driving gear, said driving gear having a shaft extending across the base from front to rear and at a right angle to the axis of the twisting pinion, a ratchet lever centered on said shaft for actuating the same, and tensioning means including an operating ratchet lever mounted on the base at the right side of the twisting gears, said levers operating in upright parallel planes from the right side of the machine and doing their twisting and tensioning work in their forward movement from the operator.

16. In a wire tying machine, the combination of a base, twisting gears comprising a pinion and driving gear, said driving gear having a shaft extending across the base from front to rear and at a right angle to the axis of the twisting pinion, a lever centered on said shaft for actuating the same, tensioning means including an operating lever mounted on the base at the right side of the twisting gears, said levers operating in upright parallel planes from the right side of the machine, and a cutter mounted between the twisting gears and tensioning means and actuated by the twisting lever.

17. In a wire tying machine, the combination of a base, twisting gears comprising a pinion and driving gear, said driving gear having a shaft extending across the base from front to rear and at a right angle to the axis of the twisting pinion, a ratchet lever centered on said shaft for actuating the same, tensioning means including an operating ratchet lever mounted on the base at the right side of the twisting gears, said levers operating in upright parallel planes from the right side of the machine and doing their twisting and tensioning work in their forward movement from the operator, and a cutter mount-

ed between the twisting gears and tensioning means and actuated by the twisting lever.

18. In a wire tying machine, the combination of a base, twisting gears comprising a pinion and driving gear, said driving gear having a shaft extending across the base from front to rear and at a right angle to the axis of the twisting pinion, a ratchet wheel fixed on said shaft, an oscillating ratchet lever loosely mounted on the shaft and acting in one direction of its throw only to rotate the shaft, tensioning means including an operating lever mounted on the base at one side of the twisting gears, said levers operating in upright parallel planes, and a cutter mounted between the twisting gears and tensioning means and actuated by the twisting lever.

19. In a wire tying machine, the combination of a base, tying means and tensioning means mounted thereon, and operating levers for said tying means and tensioning means, said levers being mounted so as to operate wholly above the base and move to and from the operator in parallel planes, and a cutter actuated by the operating lever for the tying means upon the completion of the tying operation.

20. In a wire tying machine, the combination of a base, twisting gears and a tension head mounted thereon, and hand-operated ratchet levers for said twisting gears and tension head mounted so as to operate wholly above the base and to and from the operator in parallel planes, and a cutter actuated by the operating lever for the twisting gears upon the completion of the twisting operation.

21. In a wire tying machine, the combination of a base, tying means and tensioning means mounted thereon, and operating levers for said tying means and tensioning means, said levers being mounted so as to operate wholly above the base and move to and from the operator in parallel planes and in their forward thrust from the operator actuate respectively the tying means and tensioning means, and a locking device adapted to automatically lock said tying means in predetermined position at the end of each tying operation, said locking device being located in the path of movement of the tensioning lever and disengageable thereby to permit the tying means to be operated.

22. In a wire tying machine, the combination of a base, twisting gears and a tension head mounted thereon, and hand-operated ratchet levers for said twisting gears and tension head mounted so as to operate wholly above the base and move to and from the operator in parallel planes parallel to the wire upon which the machine is operating, and in their forward thrust to actuate respectively the twisting gears and tension head, and a locking device adapted to automatically lock

said gears in predetermined position at the end of each twisting operation, said locking device being disengageable by the tensioning lever at the end of its tensioning thrust to permit the twisting gears to be operated.

23. In a wire tying machine, the combination of a base, twisting gears comprising a pinion and driving gear, said driving gear having a shaft extending across the base from front to rear and at a right angle to the axis of the twisting pinion, a lever centered on said shaft for operating the same, a locking device for automatically locking said shaft in predetermined position upon the completion of each twisting operation and tensioning means operable to disengage said locking device.

24. In a wire tying machine, the combination of a base, twisting gears comprising a pinion and driving gear, said driving gear having a shaft extending across the base from front to rear and at a right angle to the axis of the twisting pinion, a lever centered on said shaft for operating the same, a locking device for automatically locking said shaft in predetermined position upon the completion of each twisting operation and tensioning means including an operating lever operable on its throw at the end of the tensioning operation to disengage said locking device.

25. In a wire tying machine, the combination of a base, twisting gears comprising a pinion and driving gear, said driving gear having a shaft extending across the base from front to rear and at a right angle to the axis of the twisting pinion, a lever centered on said shaft for operating the same, a locking device for automatically locking said shaft in predetermined position upon the completion of each twisting operation and tensioning means including an operating lever mounted on the base at the right side of the twisting gear and operable on its throw at the end of the tensioning operation to disengage said locking device, said levers operating in parallel planes from the right side of the machine.

26. In a wire tying machine, the combination of tying means, tensioning means, and a locking device for automatically locking the tying means in predetermined position upon the completion of each tying operation, said tensioning means being operable to disengage the locking device.

27. In a wire tying machine, the combination of tying means, tensioning means, and a locking device for automatically locking the tying means in predetermined position upon the completion of each tying operation, said tensioning means being so arranged as to disengage the locking device at a predetermined point of its operation.

28. In a wire tying machine, the combination of tying means, tensioning means,

and a locking device for automatically locking the tying means in predetermined position upon the completion of each tying operation, said tensioning means including a lever operable at one point of its throw to disengage the locking device.

29. In a wire tying machine, the combination of tying means, tensioning means, and a locking device for automatically locking the tying means in predetermined position upon the completion of each tying operation, said tensioning means being operable to disengage the locking device, and a cutter automatically actuated upon the completion of the tying operation.

30. In a wire tying machine, the combination of a base, tying means and tensioning means mounted thereon, and operating levers for said tying means and tensioning means, said levers being mounted so as to operate wholly above the base and move to and from the operator in parallel planes, a cutter actuated by the operating lever for the tying means upon the completion of the tying operation, and a locking device for automatically locking the tying means in predetermined position upon the completion of each tying operation, said lever for the tensioning means being operable to disengage the locking device.

31. In a wire tying machine, the combination of a base, twisting gears and a tension head mounted thereon, and hand-operated ratchet levers for said twisting gears and tension head mounted so as to operate wholly above the base and move to and from the operator in parallel planes parallel to the wire upon which the machine is operating, and in their forward thrust to actuate respectively the twisting gears and tension head, a locking device adapted to automatically lock said gears in predetermined position at the end of each twisting operation, said locking device being operable by the tensioning lever to automatically disengage the locking device at the end of its tensioning thrust to permit the twisting gears to be operated, and a cutter mounted between the twisting gears and tension head and actuated by the twisting lever.

32. In a wire tying machine, the combination of devices for holding, tensioning and tying together two bights of wire, actuators for the tensioning and tying devices, and an ejector moved by the actuator for the tying device to cause said ejector to bear forcibly against said bights of wire after they are tied together to eject them from said machine.

33. In a wire tying machine, the combination of a slotted twisting pinion for twisting together two bights of wire and slotted wire holders located on either side of said pinion with an ejector acting to bear forcibly against the wire after it is twisted and eject

- it from the slots of said pinion and wire holders, a lever for actuating said twisting pinion, and means movable by said lever to move said ejector forcibly against the wire.
34. In a wire tying machine, the combination of a slotted twisting pinion for twisting together two bights of wire, an actuator therefor and wireholders located on either side of said pinion, with an ejector mechanism movable by said actuator to bear forcibly against the wire after it is twisted and eject it from said pinion and wire holders.
35. In a wire tying machine, the combination of wire tying means having an operating handle for tying together two bights of wire with an ejector mechanism movable by said handle and acting to bear forcibly against the wire after it is tied to free it from the tying means.
36. In a wire tying machine, the combination of devices for holding, tensioning and tying together two bights of wire, actuators for said tensioning and tying devices, an ejector movable by the actuator for the tying device to bear forcibly against the wire after it is tied and eject it from said machine, and a spring to return the ejector to initial position.
37. In a wire tying machine, the combination of devices for holding, tensioning and tying together two bights of wire, an ejector carried by said machine in cooperative relation with the tying device to positively eject said bights of wire after they are tied, and a locking device cooperating with said tying device and said ejector to lock said ejector in a predetermined position.
38. In a machine, the combination of wire tying devices for holding, tensioning and tying together two bights of wire with an ejector to free the tied wire from the machine, and a locking device for locking both the tying device and the ejector in predetermined position.
39. In a wire tying machine, the combination of tying means and tensioning means for tensioning and tying two bights of wire together with an ejector to free the tied wire from the tying means and a locking device for locking the ejector in predetermined position after its operation, said tensioning means being operable to disengage the locking device.
40. In a wire tying machine, the combination of tying means and tensioning means for tensioning and tying two bights of wire together with an ejector to free the tied wire from the tying means and a locking device for locking both the tying means and the ejector in predetermined position after their operation.
41. In a wire tying machine, the combination of tying means and tensioning means for tensioning and tying two bights of wire together with an ejector to free the tied wire
- from the tying means and a locking device for locking both the tying means and the ejector in predetermined position after their operation, said tensioning means including an actuator operable at a predetermined point in its movement to disengage the locking device.
42. In a wire tying machine, the combination of tying means and tensioning means for tensioning and tying two bights of wire together with a reciprocating ejector to free the tied wire from the tying means and a locking device for locking both the tying means and the ejector in predetermined position after their operation, said tensioning means including an oscillating lever operable at one point of its travel to disengage the locking device.
43. In a wire tying machine, the combination of tying means and tensioning means for tensioning and tying two bights of wire together with an ejector to free the tied wire from the tying means and a locking device for locking the ejector in predetermined position after its operation, said tensioning means being operable to disengage the locking device, and a cutter automatically actuated at the end of the tying operation.
44. In a wire tying machine, the combination of tying means and tensioning means for tensioning and tying two bights of wire together with an ejector to free the tied wire from the tying means and a locking device for locking both the tying means and the ejector in predetermined position after their operation, and a cutter automatically actuated at the end of the tying operation.
45. In a wire tying machine, the combination of tying means and an actuator therefor for tying together two bights of wire with an ejector to free the tied wire from the tying means and a locking device for locking the tying means in predetermined position upon the completion of each tying operation and connecting means between said actuator and ejector whereby the ejector may be operated after the tying operation has been completed.
46. In a wire tying machine, the combination of tying means for tying together two bights of wire and an operating lever therefor having an oscillating movement with an ejector to free the tied wire from the tying means, said lever being arranged on movement in one direction to operate the tying means and on movement in the other direction to operate said ejector.
47. In a wire tying machine, the combination of tying means for tying together two bights of wire and an operating lever therefor having an oscillating movement with an ejector to free the tied wire from the tying means, said lever being arranged on movement in one direction to operate the tying means and on movement in the other direction to operate said ejector, and a locking de-

vice to lock both the tying means and ejector upon the completion of their respective operations.

48. In a wire tying machine, the combination of tying means for tying together two bights of wire and an operating lever therefor having an oscillating movement with an ejector to free the tied wire from the tying means, said lever being arranged on movement in one direction to operate the tying means and on movement in the other direction to operate said ejector, a locking device to lock both the tying means and ejector upon the completion of their respective, and tensioning means operable to disengage said locking device.

49. In a wire tying machine, the combination of tying means for tying together two bights of wire and an actuator therefor with a spring returned ejector to free the tied wire from the tying means and connections between said actuator and ejector including a cam to actuate the ejector and operable by said actuator.

50. In a wire tying machine the combination of a base, tensioning means and tying means mounted on said base, levers for operating said means, and ejecting means associated with the tying means and movable by the lever which operates said tying means.

51. In a wire tying machine the combination of a base, tensioning means mounted on said base, means also mounted on said base for tying together two bights of wire received by said machine, a locking device associated with said tying means to lock said tying means in predetermined position after the wire has been tied, means associated with said tying means for ejecting the wire from said machine after completion of the tying operation, and means for operating said locking means to unlock said locking means at the beginning of a tying operation.

52. In a wire tying machine the combination of a base, tensioning means, means for tying together bights of wire received in said machine, a locking device associated with said tying means, levers for operating said tensioning means and said tying means, one of said levers operating to tension the wire and to unlock said locking device and then to steady said machine during the operation of said tying means, means for cutting one bight of wire, and means for ejecting the wire from the machine, said second lever arranged to steady the machine during the tensioning operation and to thereafter operate the tying, cutting and ejecting means.

53. In a wire tying machine the combination of a base, tensioning means and tying means mounted on said base, levers for operating said tensioning means and said tying means, a locking device associated with said tying means, means for ejecting wire from said machine after the wire has been tied,

said ejecting means being associated with said tying means, the lever for said tying means having a pawl and ratchet engagement with said tying means and arranged to operate the same to a predetermined position when said locking means automatically operates to stop further movement of said tying means, said tying lever adapted to be moved in opposite direction for purposes of operating said ejector and to be held in final position after ejection by said locking means and by a portion of said base.

54. In a wire tying machine the combination of tensioning and tying device for tying together bights of wire inserted in said machine, a lever arranged to operate said tying device, and a locking means associated with said tying device for locking the same in predetermined position, said lever in its normal operation arranged to be brought to a position substantially horizontal and to be held in this position by its association with the locked tying device, said lever then acting as a carrying handle for said machine.

55. In a wire tying machine, the combination of a base, tensioning means and tying means mounted thereon, a lever for operating said tensioning means, a lever for operating said tying means, and a locking device arranged to prevent the forward operation of said second lever after a predetermined movement of said tying means, said locking means constructed to be operated by said first lever to free said second lever for operation.

56. In a wire tying machine the combination of a base, tying means and tensioning means mounted thereon, levers for operating said tying means and said tensioning means, both levers extending from the machine in the same general direction and in lengthwise relation to bights of wire held in the machine, and ejecting means for removing the tied bights of wire from said machine, said ejecting means being moved by the lever that operates said tying means.

57. In a wire tying machine the combination of a base, tensioning means and tying means mounted on said base, levers for operating said means, and ejecting means associated with said tying means, said levers adapted to be operated to complete the operations of tensioning, twisting and ejecting bights of wire from said machine without the operator's hands being removed from said levers.

58. In a wire tying machine the combination of a base, tensioning means and tying means mounted on said base, levers for operating said tensioning and said tying means, said levers extending in the same general direction from said base and in lengthwise relation to the wire held in said machine and arranged to be grasped by an operator and operated to complete the tensioning and tying operations without the operator's hands

- being removed from said levers, and cutting means associated with said tying means and adapted to be automatically operated by the movement of one of said levers.
59. A wire tying machine having separate devices for tensioning, tying and ejecting bights of wire inserted in said machine, and two levers carried by said machine, one of said levers being associated with said tensioning device and the other lever associated with the other devices for operating the same to tie said bights of wire and to positively eject the same from said machine.
60. A wire-tying machine having separate devices for tensioning, tying and ejecting bights of wire inserted in said machine, two levers carried by said machine, said levers being associated with said devices for operating the same, and an automatic locking means associated with said tying means to lock the same in a predetermined position, said locking means being operable by one of said levers to free the tying means after said tensioning device has been operated.
61. A wire tying machine having mechanisms for tensioning, tying, cutting and ejecting bights of wire threaded into said machine, two levers carried by said machine, said levers being associated with said mechanisms for operating the same, and an automatic spring pressed locking means associated with said tying mechanism to retain the same in a predetermined position, said locking means being moved by the lever associated with the tensioning mechanism after the operation of the tensioning mechanism to free the tying mechanism, and said locking means later automatically re-engaging said tying mechanism after the completion of the tying of said bights of wire.
62. In a wire tying machine, the combination of devices for holding, tensioning and tying together two bights of wire, levers for operating said tensioning and tying devices, an ejector acting to bear forcibly against the wire after it is tied to eject it from said machine, means associated with said tying device and movable by the lever that operates said tying device for automatically actuating the ejector, and a retaining latch associated with a portion of said ejector to hold said wire from a material sidewise movement.
63. In a wire tying machine, the combination of devices for holding, tensioning and tying together two bights of wire, an ejector associated with one of said devices to eject the tied wire from said machine, and a device mounted on a portion of said ejector for retaining the wire in place during the tying operation, said device being automatically moved outwardly from the body of said machine by the movement of said ejector while retaining its same relative relation to the wire during the movement of the wire to a point where it is free of said machine.
64. In a wire machine, the combination of tying devices for holding, tensioning and tying together two bights of wire with an ejector to eject the tied wire from the machine having a device for retaining the wire in place during the tying operation, said device being movable vertically from its normal retaining position to permit the wire to be adjusted in the machine and being automatically movable horizontally by the ejector out of its normal retaining position.
65. In a wire tying machine, the combination of devices for holding, tensioning and tying together two bights of wire, levers for operating said tensioning and tying devices, an ejector movable by the same lever that operates said tying device to eject the tied wire from the machine, and a device for retaining the wire in place during the tying operation, said retaining device being arranged to automatically move horizontally out of its retaining position when the ejector operates upon the wire.
66. In a wire tying machine, the combination of a slotted twisting pinion for twisting together two bights of wire and slotted wire holders located on either side of said pinion with an ejector to free the tied wire from the pinion and wire holders, the ejector having a reciprocating thrust member to bear against the wire at one side of said pinion, and a device mounted on said member for retaining the wire in place during the tying operation and carried by said member beyond the slots of said pinion and wire holders during the ejecting operation.
67. In a wire tying machine, the combination of a slotted twisting pinion for twisting together two bights of wire and slotted wire holders located on either side of said pinion with an automatic ejector to free the tied wire from the pinion and wire holders, the ejector having a reciprocating thrust member to bear against the wire at one side of said pinion, and a device mounted on said member for retaining the wire in place during the tying operation, said device being movable from its retaining position to permit the wire to be adjusted in the machine and being carried by said member beyond the slots of said pinion and wire holders.
68. In a wire tying machine, the combination of devices for holding, tensioning and tying together two bights of wire, levers for operating said tensioning devices and said tying device, a locking device for locking the tying device in predetermined position after each tying operation, and an automatic ejector movable by the lever that operates said tying device to bear forcibly against the wire after the wire is tied to free it from said machine.
69. In a wire tying machine, the combination of tensioning means, tying means and means for locking the tying means in prede-

terminated position after each tying operation with an automatic ejector associated with said tying means for bearing forcibly against the wire after it is tied and free it from the machine.

5 70. In a wire tying machine, the combination of tensioning means, twisting means including a slotted pinion and slotted wire holders located on either side of said pinion, a locking device for said pinion to lock it in predetermined position after each twisting operation, an ejector acting to bear forcibly against the wire after it is tied and free it from said pinion and slotted holders, a cam piece to actuate the ejector in one direction and spring means to return the ejector to normal position.

10 71. In a wire tying machine, the combination of tensioning means, twisting means including a slotted pinion and slotted wire holders located on either side of said pinion, a locking device for said pinion to lock it in predetermined position after each twisting operation, an ejector acting to bear forcibly against the wire after it is tied and free it from said pinion and slotted holders, a slotted rotatable cam piece engaging the ejector to actuate it, means for rotating the cam piece in one direction, and a spring to rotate it in the other direction.

15 72. In a wire tying machine, the combination of a base, twisting gears comprising a pinion and driving gear, said driving gear having a shaft extending across the base from front to rear and at a right angle to the axis of the twisting pinion, a ratchet wheel fixed on said shaft, an oscillating ratchet lever loosely mounted on the shaft and acting in one direction of its throw only to rotate the shaft, tensioning means including an operating lever mounted on the base at one side of the twisting gears, said levers operating in upright parallel planes, a cutter mounted between the twisting gears and tensioning means and actuated by the twisting lever, a locking device adapted to automatically lock said gears in predetermined position at the end of each twisting operation, said locking device being disengageable by the tensioning lever at the end of its tensioning thrust to permit the twisting gears to be operated, a slotted rotatable cam piece mounted on the shaft of the driving gear, an ejector in engagement with and actuated by said cam piece, said cam piece being rotatable in one direction by the tensioning lever, and a spring to rotate the cam piece in the reverse direction.

20 73. In a wire tying machine, the combination of a base, twisting gears and a tension head mounted thereon, and hand-operated ratchet levers for said twisting gears and tension head mounted so as to operate wholly above the base and move to and from the operator in parallel planes parallel to the

wire upon which the machine is operating, and in their forward thrust to actuate respectively the twisting gears and tension head, a locking device adapted to automatically lock said gears in predetermined position at the end of each twisting operation, said locking device being operable by the tensioning lever to automatically disengage the locking device at the end of its tensioning thrust to permit the twisting gears to be operated, a cutter mounted between the twisting gears and tension head and actuated by the twisting lever, an ejector including reciprocating thrust rods acting to bear forcibly against the wire after it is tied and free it from the machine, a rotatable cam piece to actuate the ejector and itself actuated by the twisting lever to move the ejector in outward direction, and spring means to rotate the cam piece in the reverse direction, said ejector having wire retaining means which permit the wire to be freely adjusted in the machine and which release the wire upon the outward movement of the ejector.

25 74. In a wire tying machine the combination of devices for tensioning and tying two bights of wire together, and means for holding an end of one of said bights during tensioning and tying, a portion of said means arranged to be moved after the tying operation to carry said end of the wire to a point where the end will automatically release and drop from said machine.

30 75. In a wire tying machine the combination of devices for tensioning and tying two bights of wire together, means for holding an end of one of said bights during tensioning and tying, a portion of said means arranged to be moved after the tying operation to carry said end of the wire to a point where the end will automatically release from said machine, and a retaining member associated with said holding means for preventing the sliding of the wire sidewise.

35 76. In a wire tying machine the combination of devices for tensioning and tying two bights of wire together with a compound means for receiving and holding an end of one bight of wire and for holding a portion of another bight of wire, one portion of said compound means arranged to move relatively to another portion of said means to carry said wires to releasing position.

40 77. In a wire tying machine the combination of devices for tensioning and tying two bights of wire together, a compound means for receiving and holding an end of one bight of wire and for holding a portion of another bight of wire, one portion of said compound means arranged to slide over another portion of said means to carry said wires free of said receiving and holding means, and a retaining member associated with said means for preventing the sliding of the wire sidewise.

78. In a wire tying machine the combination of a base, tensioning means and tying means mounted on said base and adapted to receive and tie together two bights of wire, 5 actuators for operating said tensioning means and said tying means, and a compound means comprising two portions normally combined to form a recess for restraining portions of said bights of wire in predetermined position, said portions adapted 10 to be rearranged after tying operations to remove said restraint on said bights.

79. In a wire tying machine the combination of a base, tensioning means and tying 15 means mounted thereon and adapted to receive two bights of wire, one of said bights being provided with a deformed portion, and a compound means carried by said base for receiving portions of said bights of wire 20 without special attention to the positions of the wires except to have said deformed portion on one side of said compound means, a portion of said compound means being movable to slide over another portion of 25 said means to move said bights from said compound means.

80. In a wire tying machine the combination of a base, tensioning means and tying means mounted thereon and adapted to receive two bights of wire, one of said bights being provided with an upset portion, and a compound means for receiving the wire bights, a portion of said compound means being movable to another portion of said 35 means, one of said portions being recessed near its end to form a slot with said other portion, said slot being of uniform height throughout its length to receive said bights of wire side by side.

81. In a wire tying machine the combination of a base, tensioning means and tying means mounted thereon and adapted to receive two bights of wire, one of said bights being provided with an upset portion, and a compound means for receiving the wire bights, a portion of said compound means being movable to another portion of said means, one of said portions being recessed near its end to form a slot with said other portion, 50 said slot being of uniform height throughout its length to receive said bights of wire side by side, and a latch retaining means associated with said movable portion, and arranged to allow said bights to pass into said slot and to prevent said bights from slipping out of said slot, said movable portion adapted to move said wire bights along said other portion until the bights are free to be drawn from said compound means.

82. In a wire tying machine, the combination of a base, tensioning and tying devices mounted thereon and adapted to receive and tie together two bights of wire, actuators for operating said tensioning means and said tying means, a projection extending from said

machine, a movable member carried by said base and cooperating with said projection and being constructed to form a slot with said projection, a latch carried by said movable member and movable to allow said bights of wire to pass into said formed slot and to prevent said bights from coming out of said slot, and means associated with one of said actuators for moving said movable member relatively to said projection to move said bights of wire to a point where they are released from said movable member and said projection, said latch remaining in the same relation to said bights of wire until said bights move relative to said movable member.

83. In a wire tying machine the combination of a base, tensioning means and tying means mounted thereon and adapted to receive and tie together two bights of wire, 85 one of said bights having an upset head on the end thereof, means for operating said tensioning and said tying means, a movable member carried by said base and adapted to be moved relatively thereto, said member being provided with a recess in its under surface, a projection on said base and being so positioned as to be underneath the recessed part of said movable member to form a slot therewith, said projection and the recessed part of said member being in alignment with said tying means so as to receive said bights of wire, the upset head of said wire being drawn by said tensioning means against said movable member and against said projection, said movable member sustaining the major portion of the pressure exerted by said head due to the pull of tensioning as the major portion of said head engages said movable member.

84. In a wire tying machine the combination of a base, tensioning means and tying means mounted on said base, levers for operating said tensioning and tying means, a thrust rod associated with said base, and in cooperative relation with a projection from said base, said rod adapted to receive and hold a portion of a wire during tensioning and tying operations and to be assisted in holding said wire by said projection, and ejecting means associated with said tying means and with said thrust rod, the movement of said thrust rod by said ejecting means acting to carry the wire held in said thrust rod beyond said projection to permit the wire to move from said rod.

85. In a wire tying machine the combination of a base, tensioning means and tying means mounted on said base, levers for operating said tensioning means and said tying means, an ejector associated with said tying means comprising three thrust rods, one of said rods constructed to engage an upset head on a wire threaded into said machine and to move forward with the other rods

during ejecting operation to carry said upper head to a position of release.

86. In a wire tying machine the combination of devices for tensioning and tying two bights of wire received within said machine with a compound holder for receiving and holding an end of one of said bights and for receiving a portion of the other of said bights, a retaining latch carried by a portion 10 of said compound holder, the portion of said holder carrying said latch being constructed to have sliding movement along the top surface of the other portion of said holder after the tying operation has been completed to carry to the edge of said other portion the bights of wire to permit said bights to fall from said machine.

87. In a wire tying machine the combination of a base, a tensioning means mounted 20 thereon, a tying means also mounted on said base, a projection extending from said machine, a movable member arranged to slide over said projection, said movable member being provided with a recess near the end 25 thereof, said recess forming a slot with said projection, said slot adapted to receive therein the bights of wire inserted in said machine, said member and said projection, cooperating to hold said bights during tensioning and tying operations, said movable member being associated with an operating 30 part of said machine and arranged to be moved over said projection to carry said bights of wire beyond the ends of said projection.

88. In a wire tying machine, the combination of a base, a tensioning means mounted on said base, a tying means and a locking means associated therewith positioned on 40 said base, an ejecting means carried by said base, and handles for operating the several means, whereby bights of wire after being placed around a package and threaded into said machine are tensioned by said tensioning 45 means in response to the operation of the handle associated therewith, freeing said tying means by moving said tensioning handle into engagement with said locking means, tying said bights of wire together by the movement 50 of the handle associated with said tying means, said locking means being constructed to automatically lock said tying means after a predetermined movement, of said tying means and ejecting the tied bights 55 of wire from the machine by the movement of said second handle after being moved into cooperative relation with said ejecting means.

89. In a wire tying machine, the combination of a base, a tensioning means mounted 60 on said base, a tying means positioned on said base, an ejecting means also carried by said base, handles for operating the several means, and a locking means associated with said tying means for maintaining said tying 65 means in locked position, the handle associ-

ated with said tensioning means being arranged to move into engagement with said locking means to free said tying means for operation by another handle.

90. In a wire tying machine, the combination of a base, a tensioning means mounted on said base, a tying means and an automatic locking means associated therewith positioned on said base, a cutting means operable by a member of said tying means, an ejecting means carried by said base, and handles for operating the several means, whereby bights of wire after being placed around a package and threaded into said machine are tensioned by said tensioning means in response to the operation of a handle associated therewith, operating said locking means by the handle associated with said tensioning means to free said tying means, tying said bights of wire by a movement of said tying means in response to a handle associated therewith, operating said cutting means to cut an end of one of said bights of wire just before the final completion of the tying operation, locking said tying means after a predetermined movement thereof by said automatic locking means, and ejecting the tied bights of wire from said machine by the movement of the second handle after it is moved into cooperative relation with said ejecting means.

91. In a wire tying machine, the combination of a slotted twisting pinion for twisting together two bights of wire and slotted wire holders located on either side of said pinion with an ejector acting to bear forcibly against the wire after it is twisted and eject it from the slots of said pinion and said wire holders, means for operating said pinion, and means associated with said pinion operating means for automatically actuating said ejector.

92. In a wire tying machine, a slotted twisting pinion for twisting together two bights of wire, mechanism for operating said pinion, and an ejector associated with and controlled by said mechanism for forcibly moving said wire out of said pinion after said wire has been twisted.

93. In a wire tying machine, the combination of a slotted twisting pinion for twisting together two bights of wire with an ejector acting to bear forcibly against the wire after it is tied and free it from said pinion, an actuator for operating the twisting pinion and for moving the ejector in one direction, and a spring to move it in the other direction.

94. In a wire tying machine, the combination of devices for tensioning and tying together two bights of wire with a slidably reciprocating ejector acting to bear forcibly against the wire after it is tied and eject it from the tying device, an actuator for operating the tying device and for moving the

ejector against said wire, and a spring to return said ejector to its initial position.

95. In a wire tying machine devices for tensioning and tying together two bights of

5 wire, an ejector to free the tied wire from the tying device, and a locking device for locking both the tying device and the ejector in a predetermined position.

96. In a wire tying machine, the combination of a base, tensioning means mounted on said base, means for tying together two bights of wire received by said machine, an actuator for operating said tying means, and an ejector for removing said wire from said 10 machine after being tied, said ejector having co-operative relation with said tying means to automatically eject the wire after it has been tied.

97. In a wire tying machine, the combination of a twister constructed to receive and twist together two bights of wire, means for operating said twister, an ejector member positioned close to one side of said twister and arranged to be moved to positively push 25 said bights of wire out of said twister after the bights have been twisted, and automatic means associated with and controlled by said operating means for moving said ejector member.

98. In a wire tying machine, the combination of a base, a tying device mounted on said base for receiving and tying together two bights of wire, a lever for said tying device, said lever arranged to operate in a plane 30 parallel to said bights of wire as they are held in said machine, and an ejector for positively moving said bights of wire out of said machine after they have been tied together, said ejector being automatically operated by said lever.

99. In a wire tying machine, the combination of a base, a tensioning device mounted on said base and arranged to tension bights of wire held in said machine, a tying device 45 also mounted on said base and arranged to receive and tie together the bights of wire, levers for operating said tensioning device and said tying device, said levers extending in the same general direction and being in 50 substantial parallel relation to the bights of wire as held in said machine, and an ejector for positively moving said bights of wire out of said machine after they have been tied, said ejector being automatically operated by 55 one of said levers.

100. In a wire tying machine a base, a tying device mounted on said base and being constructed to receive and tie together two 60 bights of wire, a handle for operating said tying device, said handle extending in a plane substantially parallel to the bights of wire held in said tying device, and an ejector automatically operated by said handle for 65 positively ejecting said bights of wire from

said machine after they have been tied.

In testimony whereof we have signed our names to this specification.

JOHN A. RIETMANN.
ALEX RADICS.
